UNITED STATES PATENT OFFICE

107,179

DESIGN FOR A DISPLAY STAND

John G. Toomey, New York, N. Y., assignor to Park & Tilford, New York, N. Y., a corporation of New York

Application September 10, 1937, Serial No. 71,543

Term of patent 7 years

To all whom it may concern:

Be it known that I, John G. Toomey, a citizen of the United States, residing in Bronx County and State of New York, have invented a new, original, and ornamental Design for a Display Stand, of which the following is a specification, reference being had to the accompanying drawing, forming a part thereof.

Fig. 1 is a perspective view of a display stand showing my new design.

Fig. 2 is a side view thereof, the base being shown partially broken away.

Fig. 3 is a rear view.

Fig. 4 is a partial sectional view taken on line
4—4 of Fig. 1.

I claim:

The ornamental design for a display stand as shown.

JOHN G. TOOMEY.
